UNITED STATES PATENT OFFICE.

ADOLF ROSZKOWSKI, OF NEW YORK, N. Y.

COMPRESSOR.

REISSUED

1,383,860.

Specification of Letters Patent.

Patented July 5, 1921.

Application filed February 9, 1920. Serial No. 357,485.

To all whom it may concern:

Be it known that I, ADOLF ROSZKOWSKI, a subject of Russia, residing at 206 Broadway, New York, in the county of New York and 5 State of New York, have invented certain new and useful Improvements in Compressors, of which the following is a specification.

This invention relates to an improvement 10 in automatic air compressor apparatus, designed particularly for use with an improved compressed air supply system for railroad stations forming the subject matter of Patent No. 1,240,373 issued to me September 18, 1917.

Briefly, such system comprises reservoirs containing water and compressed air located beneath the surface of the ground at the water station, the reservoirs being connected with each other, with a more or less remote pump station for the supply of water and air to such reservoirs, and with a stand-pipe outlet from which the water is withdrawn for use. A particular valve arrangement between the reservoirs, supply and service pipes renders the system self distributing and self regulating.

The system contemplates the continued use of the compressed air of the reservoirs, 30 that is the use of such air as a motive force for the water to a low limit of pressure of such air and the restoration of the maximum air pressure through an additional supply of water from the pump station.

In the practical use of such system, however, it has been found that there is a distinct but slow dissolution of the compressed air in the water, and as such is lost for effective uses, it must be compensated for, 40 preferably by replacement.

The present invention is designed to provide an apparatus for the automatic replacement of such dissolved or absorbed portion of the compressed air, and in more specific 45 detail comprises two comparatively small tanks, preferably located at or near the pump station of the system and on a level below that of the reservoirs. Two-way valves, connected for simultaneous but reverse action, are provided, either serving to 50 connect a particular tank with the water pipe from the reservoir and air pipe thereto, while the other at the same time connects the other tank, at both inlet and outlet with 55 the atmosphere. The reservoir connected

tank, which by a previous position of the valve has been connected with the atmosphere and is therefore filled with air under atmospheric pressure, is subjected to the pressure of the water from the reservoirs, 60 under the head incident to the difference in level, and the contained air forced into the system. The other tank, which in the previous position of the valves has gradually filled with water from the reservoirs in forcing the air therefrom into the system, is in the present position of the valves, open to the atmosphere, draining it of water and, of course, filling it with air under atmospheric pressure to be forced into the system when 70 the valves are reversed.

In the drawings:

Figure 1 is a view illustrating more or less diagrammatically the improved compressor apparatus.

Fig. 2 is a section of the valve.

The improved construction comprises two tanks, 1 and 2, preferably located near the pump station of the improved system, and on a level below the service reservoirs of 80 such system to provide a head of water from the service reservoirs to the tanks through the pipe 3, leading from such service reservoirs.

An air supply pipe 4 leads to the air pressure pipe for serving the reservoirs, and this pipe has a valve 5 which opens toward the reservoirs.

Tank 1 has an air pipe 6 opening therefrom near the top with a water excluding 90 valve 7 at the entrant end thereof, and also a water pipe 8 opening therefrom near the bottom; while tank 2 has exactly similar pipe arrangement, that is air pipe 9, with valve 10, and water pipe 11.

Control valves 12 and 13 are provided for the compressor, these valves each having two non-communication passages 14 and 15. The valves are connected, as by a rod or other appropriate means 16, whereby such 100 valves are simultaneously operated, but with the parts thereof relatively reversed under all working conditions.

The respective valve casings 17 and 18, are each provided with a port 19, leading 105 to the atmosphere, the casing 17 of valve 12 having ports 20 and 21 for the connection thereto of the air pipes 6 and 9 of the respective tanks, and another port 22 for the connection of the air supply pipe 4. The cas-

ing 18 of valve 13 has similar ports, that is ports 23, 24 for connection of the respective water pipes 8 and 11 of the tanks 1 and 2, and a port 25 to which the pipe 3 is connected.

The passages 14 and 15 of the valves are so relatively disposed that in one position for example that illustrated in the drawings, the air and water pipes of tank 1 are open 10 to the atmosphere, and hence this tank is charged with air under atmospheric pressure. The air and water pipes of tank 2, however, are in this position of the valves connected with the water pipe 3 and air supply pipe 4 of the system. The water under the head described, will force the air from tank 2 into the system to replenish the absorbed air. When tank 2 has become substantially filled with water, as may be indicated as an external gage 26, the valves are operated by means 16 to reverse them, utilizing tank 1 as the service tank, and opening tank 2 to the atmosphere for drainage of the water therefrom and replacement of such 20 water with air for charging purposes on the next operation of the valves.

Beyond the mere change of the valves, the compressor apparatus is entirely automatic in its operation, and will effectively maintain a constant air volume in the system.

Claims:

1. An air compressor for water systems using compressed air as a motive power, comprising two tanks, arranged to have a 35 water head from the system, and means for simultaneously connecting one tank with such water head and compressed air service of such system and the other tank with the atmosphere.
2. An air compressor for water systems using compressed air as a motive power, comprising two tanks, arranged to have a water head from the system, and means for simultaneously connecting one tank with 45 such water head and compressed air service of such system and the other tank with the atmosphere, said means being reversible with respect to the tanks at will.
3. An air compressor for water systems 50 using compressed air as a motive power, comprising two tanks, arranged to have a water head from the system, a valve for connecting each tank either with the water head

from the system and the compressed air service, or with the atmosphere at will. 55

4. An air compressor for water systems using compressed air as a motive power, comprising two tanks, arranged to have a water head from the system, a valve for connecting each tank either with the water head 60 from the system and the compressed air service, or with the atmosphere at will, and means for simultaneously and reversely operating said valves with respect to the tanks.

5. An air compressor for water systems 65 using compressed air as a motive power, two tanks arranged below the system to provide a water head therefrom, a water pipe leading from the system, a compressed air pipe leading to the compressed air service of the 70 system, an air pipe leading from the top of each tank, a water pipe leading from the bottom of each tank, and a two way valve for each tank, one of said valves having passages adapted in the operation of the 75 valve to connect the air pipe of one tank with the system compressed air pipe and the air pipe of the other tank with the atmosphere, the other of said valves having passages to connect the water pipe of one 80 tank with the system water pipe and the water pipe of the other tank with the atmosphere.

6. An air compressor for water systems using compressed air as a motive power, two 85 tanks arranged below the system to provide a water head therefrom, a water pipe leading from the system, a compressed air pipe leading to the compressed air service of the system, an air pipe leading from the tops of 90 each tank, a water pipe leading from the bottom of each tank, and a two way valve for each tank, one of said valves having passages adapted in the operation of the valve to connect the air pipe of one tank with the 95 system compressed air pipe and the air pipe of the other tank with the atmosphere, the other of said valves having passages to connect the water pipe of one tank with the system water pipe and the water pipe of the 100 other tank with the atmosphere, and means to connect the valves for simultaneous operation to connect one tank in the system while opening the other to the atmosphere.

In testimony whereof I affix my signature. 105
ADOLF ROSZKOWSKI.
